UNITED STATES PATENT OFFICE.

HORACE RESLEY, OF CUMBERLAND, MARYLAND.

MEANS FOR RADIATING CAR-TRUCKS.

SPECIFICATION forming part of Letters Patent No. 480,830, dated August 16, 1892.

Application filed April 28, 1892. Serial No. 430,999. (No model.)

To all whom it may concern:

Be it known that I, HORACE RESLEY, a citizen of the United States, and a resident of Cumberland, in the county of Allegany and 5 State of Maryland, have invented certain new and useful Improvements in Railroad-Car Mounting; and I do hereby declare the following to be a full, clear, and exact description of the invention, such as will enable others 10 skilled in the art to which it appertains to make and use the same.

My present invention relates to railroad-car mounting, and is designed, primarily, as an improvement on my patent, No. 441,976, dated 15 December 2, 1890.

The rocking motion of railroad-cars, especially in rounding curves, throws the greater weight toward the inner rail, thereby lessening the weight on the outer rail and tending 20 to make the truck jump the track. My invention aims to avoid this danger by automatically adjusting the trucks to the rails so that their axles will be in the radial lines of the curve, which causes the train to move 25 easily along the track without throwing the weight of the train disproportionately on either rail and preventing the wheels of the train from impinging against the outer rail.

With these ends in view the invention 30 templates a swinging post pivoted or hinged to a plate secured on the car-body above the ends of each upper bolster, which post operates in a countersunk portion of a bearing-plate secured on the upper bolster, said bearing-plate being bent upward to provide a rest 35 for the car-body on turning a curve.

My invention further consists of the construction and arrangement of parts, as will be hereinafter fully described and claimed.

40 To enable others to readily understand the invention, I have illustrated the same in the accompanying drawings, in which—

Figure 1 is a side elevation. Fig. 2 is a transverse sectional view on the line $\alpha\alpha$ of 45 Fig. 1. Fig. 3 is a detail view showing the position of the swinging post on the inner end of the bolster when rounding a curve. Fig. 4 is a detail view showing the position of the swinging post on the outer end of the 50 bolster when rounding a curve.

Referring to the drawings, in which like letters of reference denote corresponding parts in all the figures, A designates the bottom of the car-body, and B B the trucks, which are pivotally connected to the car-body by king-bolts a . The lower bolster b is connected with the cross-piece b' on the truck by pins or bolts C, and suitable coiled or elliptical springs c are interposed between the lower bolster and the cross-piece on the bolts C or 60 other bolts to provide a yielding bed for the car. At the outer end of each lower bolster, on the upper side thereof, is a bearing-plate D, which is partially or wholly countersunk, as desired, and is constructed and bent to form 65 a depressed seat d and a shoulder d' in front of said seat. This plate is rigidly secured to the bolster in a suitable manner, and by countersinking the same it is more effectually held from displacement. The bearing-plate is 70 preferably made of one piece of metal; but this is not essential, and it may be constructed of two or more pieces and solid at d' , if desired. Above these plates, on the outer end of each upper bolster E, is a plate e , which is countersunk, preferably, and provided with an upwardly-extending offset or shoulder e' , which affords a firm hold upon the bolster and prevents a backward strain, and displacement of 75 the plate. A swinging post or spar F is pivoted or hinged to the plate e at one end, and it extends downward and rests in the seat d of each bearing-plate on the lower bolster. It will be observed that these swinging posts are pivoted on opposite ends of the plates e 80 on the same side of the car and on the same ends of said plates on the opposite ends of the bolsters for a purpose hereinafter described. These plates e and swinging posts F are preferably made of strong metal, as 85 they are designed to partially sustain the weight of the car and are subjected to the various uneven and unusual movements of the car, which they are designed to obviate.

The operation of my improvements may be 90 stated as follows: When the car is traveling along a straight track, the swinging posts will be inclined at a slight angle to the body of the car and fitted in the seats d of the bearing-plates, the swinging posts on the same 95 100

side of the car being inclined reversely toward each other and the shoulders d' being on opposite sides of said posts. When the car is rounding a curve, the outer rail being 5 always higher than the inner rail the outer edge of the car-body and outer sides of the trucks approach each other, which is also largely due to centrifugal action; but the swinging posts on the inner side of the car-body 10 will assume a vertical position and maintain the car in its proper level. As the car reaches and begins the curve, the increased pressure on the outer side of the car forces the swinging posts in the direction in which they are 15 inclined reversely to each other, and this forces the outer ends of the front truck forward and the corresponding end of the rear truck backward. This position of the trucks will thus bring the axles thereof into diagonal positions with reference to each other and the axes of the wheels into the radial lines of the curve, which adapts the truck to move easily and smoothly around the curve without unduly impinging against the rails. At 20 25 the same time the inner ends of the trucks will move toward each other, and the swinging posts will thus be forced into a vertical position and elevate the inner side of the car-body, keeping the car-body in a level position.

To relieve the swinging posts of as much strain and weight as possible, the shoulders d' are provided, and the outer side of the car may rest partially upon said shoulders as the 30 curve is being rounded. When the curve is rounded, the devices will automatically return to their original positions.

My improvements may be adapted to all kinds of railway-cars, locomotive-trucks, and 35 40 to other cars or vehicles.

I am aware that changes in the form and proportion of parts and details of construction of my invention may be made without departing from the spirit or sacrificing the 45 advantages thereof, and I therefore reserve the right to make such changes as fairly fall within the scope of the same.

Having thus fully described my invention, what I claim as new, and desire to secure by 50 Letters Patent, is—

1. The combination, with the trucks of a car and the body mounted thereon, of the swinging posts hinged to the car-body and arranged to bear against the truck-bolster and

adjust the trucks to a curve of the track, substantially as described. 55

2. The combination, with the trucks of a car and the body mounted thereon, of the bearing-plates on the lower bolster and the swinging posts hinged at one end to the car- 60 body and adapted to bear at their free ends against said plates, substantially as and for the purpose described.

3. The combination, with the trucks of a car and the body mounted thereon, of the 65 bearing-plates secured on the lower bolsters and having depressed seats and the posts depending from the body and fitted in said seats and adapted when rounding a curve to adjust the trucks so that the axles thereof will 70 be in the radial lines of the curve, substantially as described.

4. The combination, with the trucks of a car and the body mounted thereon, of the 75 swinging posts pivotally secured to the car-body or upper bolsters and the bearing-plates on the lower bolsters, having seats to receive the free ends of said posts, substantially as and for the purpose described.

5. The combination, with the trucks of a 80 car and the body mounted thereon, of the swinging posts pivotally hung from the upper bolsters and the bearing-plates secured on the lower bolsters beneath said posts and having seats to receive the free ends of the posts 85 and also provided with the shoulders to sustain the car-body, substantially as described.

6. The combination, with the trucks of a car and the body mounted thereon, of the lower bolsters on the trucks and the upper 90 bolsters on the body of the car, the bearing-plates secured on the lower bolsters, and the shoulders on said plates to receive the weight of the car, substantially as described.

7. The combination, with the trucks of a 95 car and its body mounted thereon, of the bearing-plates secured on the lower bolsters and having depressed seats therein, the plates secured to the upper bolsters, and the swinging posts pivoted or hinged to said plates and 100 having their free ends fitted in said seats in the bearing-plates, substantially as described.

In testimony whereof I affix my signature in presence of two witnesses.

HORACE RESLEY.
